UNITED STATES PATENT OFFICE.

HENRI FRANCIS HÉBRARD, OF PARIS, FRANCE.

DEVICE FOR TRANSMITTING MOTION TO GYROSCOPIC BODIES.

1,311,509.

Specification of Letters Patent. Patented July 29, 1919.

Application filed March 23, 1918. Serial No. 224,359.

To all whom it may concern:

Be it known that I, HENRI FRANCIS HÉBRARD, citizen of the Republic of France, and resident of Paris, France, (post-office address 6 Rue Antoine Chantin,) have invented a new and useful Device for Transmitting Motion to Gyroscopic Bodies, which improvements are fully set forth in the following specification.

10 The object of the present invention is a transmission device which allows a gyroscopic body such as for instance a gyrostat to be started and kept in motion without disturbing its equilibrium.

15 The device consists essentially in the combination of a transmission gear comprising a universally-mounted ring the center of oscillation of which is near the center of oscillation of the gyroscopic body, and of 20 an intermediate clutch between the ring and gyroscopic body constituted by pawls, balls or other suitable means.

This device enables a gyroscopic body of any size to be set in motion; it may also be 25 used with all apparatus or instruments in which gyroscopic bodies are used, such as gyroscopic tops, leveling mirrors, gyroscopic inclinometers, automatic stabilizing devices for aeronautical or marine purposes 30 and so forth.

The power for this transmission gear may be pneumatic, hydraulic, gaseous, steam or electrical.

In order to render as clear as possible the 35 explanation given below, reference is made to the accompanying drawing which shows by way of example a vertical sectional view of one form of device for transmission of motion constructed according to the present 40 invention.

The device consists essentially of a gyrostat A supported by the needle bearing B in a step bearing or cup C of hardened steel, the point of the needle forming the 45 center of oscillation of the gyrostat. The sleeve D surrounding the spindle E of the bearing C revolves freely on bronze rings F. It carries at its upper part two lugs G, and at its lower part a gear H actuated 50 by the driving pinion J. The lugs G support by means of pivots the universal joint ring K which latter carries the cylindrical bridge piece L by means of pivots arranged at an interval of 90° in relation to those 55 on the lugs G. The ring K is thus enabled to rock or oscillate about two axes which

intersect each other at right angles, one of such axes being constituted by the pivots on said ring, and the other by the pivots on the lugs G. The point of intersection of 60 these two axes thus forms the center of oscillation of the said ring, and this point, as will be observed, is near the center of oscillation of the gyrostat A, i. e., the point of 65 the needle B. The upper surface of the bridge piece is provided with a ratchet crown with which engage pawls M provided on the gyrostat A and serving to drive the latter.

The sleeve D is rotated by a motor driving 70 the pinions J and H and this motion is transmitted through the lugs G to the ring K and thence to the bridge piece L, the ratchet on the latter operating the pawls on the gyrostat A and causing the same to 75 revolve. Lateral displacement of the needle bearing B in the cup bearing C (whether due to acceleration or to retardation or to centrifugal forces) makes it necessary for the pivots of the ring K to have a certain 80 amount of play in order to avoid jamming.

The ratchet and pawl arrangement allows the gyrostat A to continue its gyroscopic motion with a practically constant speed in spite of any momentary retardation of the 85 motor.

I claim:

1. In a device of the character described, the combination of a gyroscopic body; and a transmission gear for rotating said body 90 comprising a universally-mounted member, the center of oscillation of which is located near the center of oscillation of said body, and a driving clutch interposed between said member and said body. 95

2. In a device of the character described, the combination of a gyroscopic body; and a transmission gear for rotating said body comprising a driving wheel, a spindle on which said wheel freely rotates, a pair of 100 upstanding, oppositely-located lugs carried by said wheel; a ring pivotally connected at diametrically-opposite points to said lugs, a bridge pivotally mounted on said ring, the bridge pivots being disposed at 90° in relation to the ring pivots, and a driving clutch interposed between said bridge and said body. 105

3. In a device of the character described, the combination of a gyroscopic body; and a 110 transmission gear for rotating said body comprising a driving wheel, a spindle on

which said wheel freely rotates, a pair of upstanding, oppositely-located lugs carried by said wheel, a ring pivotally connected at diametrically-opposite points to said lugs, a bridge pivotally mounted on said ring and having its upper surface ratcheted, the bridge pivots being disposed at 90° in relation to the ring pivots, and means carried by said body for engagement with said ratchet surface, thereby to effect the rotation of said body.

4. In a device of the character described, the combination of a gyroscopic body; and a transmission gear for rotating said body comprising a universally-mounted member, the center of oscillation of which is located near the center of oscillation of said body, said member being provided with a ratchet, and means carried by said body for engagement with said ratchet, to effect the rotation of the former.

5. In a device of the character described, the combination of a gyroscopic body; and a transmission gear for rotating said body comprising a pivotally-mounted ring, means for rotating the same, a bridge pivotally mounted on said ring and provided with a ratchet, and means carried by said body for engagement with said ratchet, to effect the rotation of the former.

6. In a device of the character described, the combination of a gyroscopic body; and a transmission gear for rotating said body comprising a pivotally mounted ring, means for rotating the same, a bridge pivotally mounted on said ring, the bridge pivots being disposed at 90° in relation to the ring pivots, and a driving clutch interposed between said bridge and said body.

40 7. In a device of the character described, the combination of a vertical spindle provided with a cup at its upper end; a gyroscopic body provided with a depending needle bearing engaging said cup, a universally-mounted member having its center of oscillation located close to the center of oscillation of said body, means for rotating said member, and a driving clutch interposed between said member and said body to 50 rotate the latter from the former.

8. In a device of the character described, the combination of a vertical spindle provided with a cup at its upper end, a gyroscopic body provided with a depending needle bearing engaging said cup, a universally-mounted member having its center of oscillation located close to the center of oscillation of said body, said member being provided with a ratchet; means for rotating said member, and means carried by said body for engagement with said ratchet, to transmit the rotation of said member to said body.

9. In a device of the character described, the combination of a vertical spindle provided with a cup at its upper end, a gyroscopic body provided with a depending needle bearing engaging said cup, a driving wheel freely rotatable on said spindle, driving means therefor, a pair of upstanding lugs carried by said wheel, a ring pivotally connected at diametrically-opposite points to said lugs, a bridge pivotally mounted on said ring, the bridge pivots being disposed at 90° in relation to the ring pivots, and a driving clutch interposed between said bridge and said body.

10. In a device of the character described, the combination of a vertical spindle provided with a cup at its upper end, a gyroscopic body provided with a depending needle bearing engaging said cup, a driving wheel freely rotatable on said spindle, driving means therefor, a pair of upstanding lugs carried by said wheel, a ring pivotally connected at diametrically-opposite points to said lugs, a bridge pivotally mounted on said ring and having its upper surface ratcheted, the bridge pivots being disposed at 90° in relation to the ring pivots, and means carried by said body for engagement with said ratchet surface, thereby to effect the rotation of said body.

In testimony whereof I have signed this specification in the presence of two subscribing witnesses.

HENRI FRANCIS HÉBRARD.
